UNITED STATES PATENT OFFICE

2,041,181

FEED GRINDER AND BLOWER

John Helland-Letz, Crown Point, Ind., assignor
to The Letz Manufacturing Company, a corpora-
tion of Indiana

Application February 15, 1933, Serial No. 656,895

4 Claims. (Cl. 83—8)

The present invention is directed generally to feed grinders, but more particularly to combination feed grinder and blower in which the fan wheel of the blower forms the plate holder for the revolving grinding plate.

One of the objects of the present invention is to provide a simple, compact and novel form of a combination feed grinder and blower in which a fan housing is attached to the side of the grinder and a novel arrangement is provided for adjusting the fan wheel and plate holder with respect to the stationary plate holder from the base of the grinder.

A still further object of the invention is to provide a novel and improved construction of a combination feed grinder and blower in which the number of parts are reduced to a minimum and in which the cooperating parts thereof are so arranged that a quick adjustment may be effected for grinding various types of forage.

These and other objects are accomplished by providing a construction and an arrangement of the various parts in the manner hereinafter described and particularly pointed out in the appended claims.

Referring to the drawing:

Fig. 1 is a side elevational view of my improved form of grinder and blower;

Fig. 2 is an end elevational view of the same;

Fig. 3 is a cross sectional view taken on the line 3—3 in Fig. 1;

Fig. 4 is a cross sectional view taken on the line 4—4 in Fig. 2; and

Fig. 5 is a fragmentary cross sectional view taken on the line 5—5 in Fig. 2.

In illustrating one form of my invention I have shown the same in connection with a somewhat conventional form of grinder which includes the usual form of concave or base plate, generally indicated by the reference character 10, which in turn is supported by the usual supporting frame or legs 11, rigidly connected together by means of braces 12. Mounted in the bearing 13 carried by the base plate 10, is a main drive shaft 14. The other end of the shaft is journaled in a bearing hereinafter described. Secured to one end of the shaft 14 is a pulley wheel 15. Extending from the concave or base plate 10 is the usual hopper generally indicated by the reference character 16. Secured to the shaft 14 within the concave or base plate 10, is a conveyor screw 17. Positioned above the conveyor screw and journaled in suitable bearings in the hopper 16 is a feeder or screw 18 which is operatively driven by means of a gear 19, secured to one end of the conveyor screw 18.

This gear 19 meshes with and is operatively driven by a pinion 20, secured to the shaft 14. Secured to the other side of the grinder proper and preferably to the concave or base plate 10 is a fan housing supporting casting, generally indicated by the reference character 21, which is provided with a central bore or opening, as shown at 22, which surrounds the shaft and screw 17 and permits the passage of the material therethrough to the grinding plate. This housing casting 21 is secured to the concave or base plate 10 by means of bolts 22^a which extends through oppositely disposed ears 23 formed integrally with the base plate 10. Mounted in a circular recess 24 in the casting 21 is a plate holder support 25 which in turn has located inwardly thereof a plate holder 26. The plate holder 26 is pivotally supported on a vertical axis within the plate supporter by means of vertical pins 27 so as to make the grinding plate self aligning. Secured to the plate holder 26 is a stationary grinding plate or burr 28. Secured to one side of the casting 21 is a fan or blower housing, generally indicated by the reference character 29. The housing 29 is fastened to the casting 21 by means of bolts 30 which extend through three arms 31 of a housing bracket 32. The housing bracket 32 is a circular member and is provided with an opening in the center thereof so as to admit air into the housing or opening 33 on one side of the housing. The other end of the main shaft 14 is journaled in a bearing sleeve 34. The sleeve 34 is free to move longitudinally through the opening 33 of the housing 29 with respect to the bracket 32. Mounted in a recess in one end of the bearing sleeve 34 is an end thrust bearing 35 which bears against the end of the shaft 34 and is held in the recess in the sleeve by means of a cap plate 36 secured thereto by means of bolts 37. Formed on the upper and lower sides and extending vertically from the sleeve 34 are circular lugs 38 which in turn engage semi-circular recesses 39 formed in the center portion 40 of an adjustable yoke member 41. The yoke member 41 is provided with two outwardly extending arms 42, at the outer ends of which, are apertures 43 through which two longitudinally extending rods 44 extend. The inner ends of these rods converge, as shown at 45, and have their inner ends provided with eyes which are connected by means of bolts 46 to the upper surface of the concave or base plate 10, as clearly shown in Fig. 3 of the drawing. The intermediate portions or parallel extending longitudinal portions of these rods 44 are seated in recesses 47 formed in the opposite sides of the casting 21 and 55

in similar recesses 48 mounted in the periphery or flanges of the side walls of the fan housing 29 as clearly shown in Fig. 4 of the drawing. The outer ends of these rods 44 are threaded with one 5 of them provided with a threaded nut 49 and the other with a threaded hand wheel 50 for adjusting the thrust bearing sleeve 34 by means of which the revolving grinding plate may be adjusted with respect to the stationary grinding plate for grinding different types of forage in the manner hereinafter described. Secured to the main shaft 14 within the fan housing 29 is a combination fan wheel and plate holder, clearly indicated by the reference character 51. This fan wheel is secured to the shaft 14 by means of a pin 52. Secured to the fan wheel at equally spaced apart distances are a plurality of fan blades 53, which are secured to one side of the flange or disc 54 of the fan wheel 51. Secured to the other side of 10 the disc 54 is a rotating grinding plate 55, which in turn is adapted to cooperate with the stationary grinding plate 28 for grinding the material therebetween.

The operation of my improved feed grinder and 25 blower is as follows:

Should the operator be desirous of adjusting the rotary grinding burr 55 with respect to the relatively stationary burr 28, this may be accomplished by turning the hand wheel 50 and there- 30 by move the thrust bearing sleeve 34 in a direction toward or away from the mill proper. In so doing, the shaft 14 is moved longitudinally carrying with it the fan wheel 51 as well as the burr or grinding plate 55, which is carried by the fan 35 wheel 51. In order to adjust the burrs for a coarser forage, the thrust bearing sleeve 34 is moved in a direction away from the machine or main frame by adjusting the yoke in a direction away from the main frame. As soon as the ma- 40 terial to be ground reaches the grinding burrs the shaft 14 and grinding burr 55 is moved outwardly until the thrust of the outer end of the shaft bears against the thrust bearing sleeve 34. When a finer forage is required, the thrust bearing 45 collar 34 is moved inwardly by adjusting the yoke 42 in a direction inwardly towards the frame. In this connection it will be observed that by reason of the yoke member 41 supporting the outer bearing of the shaft 14 and the rods 44 engaging 50 circular walls of the fan housing 29, all of these parts are supported in proper alignment directly to the main frame or concave member 10 by reason of the rods being secured thereto. It will also be observed that by reason of the fan plate 53 55 extending radially from the fan wheel 51 and extending inwardly into the path of the falling ground material, the fan effectively operates to discharge the material through the discharge spout 56 secured tangentially to the fan housing. It will be further noted that by supporting the outer thrust bearings of the main drive shaft as 60 well as the rotating grinding plate therewith directly to the base or concave of the frame, it is possible to make a relatively light construction fan housing and generally simplify the construction of my improved combination feed grinder and blower.

While in the above specification I have de- 70 scribed one embodiment which my invention may assume in practice, it will of course be understood that the same is capable of modification and that other modifications may be made without departing from the spirit and scope of the invention 75 as expressed in the following claims:

What I claim is my invention and desire to secure by Letters Patent is:

1. A feed grinder and blower comprising a frame, a main drive shaft mounted on said frame, a relatively stationary grinding plate secured to 5 said frame, a fan housing secured to one side of said frame, a fan wheel secured to said shaft within said housing and having a plurality of radially disposed blades secured to one side thereof, a rotary grinding plate secured to the other side 10 of said fan wheel, a radial and end thrust bearing supporting one end of said shaft including a sleeve adjustable longitudinally through an opening on one side of said housing, a yoke member for supporting said bearing, two longitudinally 15 extending rods connected to said yoke at one of their ends and rigidly secured to said frame at the other of their ends, whereby said yoke may be adjusted for varying the position of said rotary grinding plate with respect to said stationary 20 plate.

2. A feed grinder and blower comprising a frame, a main drive shaft mounted on said frame, a relatively stationary grinding plate secured to 25 said frame, a fan housing secured to one side of said frame, a fan wheel secured to said shaft within said housing, a rotary grinding plate secured to said fan wheel adjacent said stationary plate, a yoke member extending across one side of said housing, an end thrust bearing 30 oscillatably mounted in said yoke, and two longitudinally extending rods secured to said frame and adjustably connected to said yoke and engaging said housing for permitting said rotary plate to be adjusted with respect to said station- 35 ary plate and maintaining said housing in proper alignment with respect to said frame.

3. A feed grinder and blower comprising a frame, a main drive shaft mounted on said frame, a relatively stationary grinding plate secured to 40 said frame, a fan housing secured to one side of said frame, a fan wheel secured to said shaft within said housing and having a plurality of radially disposed flat blades secured to one side 45 thereof, a rotary grinding plate secured to the other side of said fan wheel, portions of said fan blades extending into a plane passing through the surfaces of said plates, an end thrust sleeve supporting one end of said shaft and means connected with said frame and oscillatably connected to 50 said sleeve for adjusting said shaft longitudinally of said stationary plate.

4. A feed grinder and blower comprising a frame, a main drive shaft journaled on said frame, a relatively stationary grinding plate secured to 55 said frame on one side thereof, a fan housing surrounding said grinding plate and secured to one side of said frame, a fan wheel secured to said shaft within said housing, a plurality of fan blades extending radially from one side of said 60 fan wheel, a rotary grinding plate secured to said fan wheel on the other side thereof, a thrust bearing on one end of said shaft, a yoke having an oscillatable connection with and for supporting said thrust bearing, longitudinal rods having their inner ends converging and secured to said frame and their outer ends adjustably secured to said yoke, certain portions of said rods engaging the side walls of said housing whereby said 65 yoke may be adjusted for adjusting the relative position of said plates with respect to each other and maintaining said housing in proper alignment with said frame.
